UNITED STATES PATENT OFFICE.

LESTER C. FRASER, OF LOS ANGELES, CALIFORNIA, ASSIGNOR OF ONE-HALF TO INEZ M. WALCOTT, OF LOS ANGELES, CALIFORNIA.

OIL-GAS BURNER.

1,417,159.

Specification of Letters Patent. Patented May 23, 1922.

Application filed September 4, 1919. Serial No. 321,537.

To all whom it may concern:

Be it known that I, LESTER C. FRASER, a citizen of the United States, residing at Los Angeles, in the county of Los Angeles 5 and State of California, have invented a new and useful Oil-Gas Burner, of which the following is a specification.

The device forming the subject matter of this application is a burner, and the invention 10 aims to provide a structure of the kind mentioned wherein the arch is of one piece construction, novel means being provided for connecting the ends of the arch with the base of the burner.

Another object of the invention is to improve the construction of the shield or guard 15 which cooperates with the arch of the burner.

It is within the province of the disclosure 20 to improve generally and to enhance the utility of devices of that type to which the invention appertains.

In the drawings:—

Figure 1 shows in top plan, a device constructed in accordance with the invention; 25 Figure 2 is a side elevation wherein parts are broken away; and Figure 3 is a fragmental section taken on the line 3—3 of Figure 2.

In carrying out the invention, there is provided a hollow base 1 having side nipples 2 and a depending part 3 supplied with an inlet 4. The numeral 5 marks a one-piece arch, the ends 6 of which are right and 30 left hand threaded into the nipples 2. The arch has resiliency enough so that the ends 6 thereof can be made to cooperate with the nipples 2 of the base 1, and by rotating the base, or by swinging the arch around the 35 base, the ends 6 of the arch may be threaded into the nipples 2. The structure thus far described is of simple two-piece construction. Adjacent to its crown, the arch 5 is supplied with a downwardly opening combustion orifice 7.

The numeral 8 marks an upwardly extended U-shaped guard straddling the crown of the arch 5 and including side wings 9 and a connection 10 uniting the 40 side wings. The guard 8 is held frictionally on the crown of the arch 5. The ends

of the connecting portion 10 of the guard engage with the lower curve of the crown of the arch 5, the central portion of the connection 10 being spaced slightly from the inner curve of the arch, adjacent to the combustion orifice 7. The side wings 9 are supplied with outwardly extending trough-shaped parts 11 having communication with the space between the connecting portion 10 60 of the guard and the crown of the arch 5.

In practical operation, the fuel is delivered into the base through the inlet 4 and passes to the combustion orifice 7. The flame at the combustion orifice 7 passes upwardly between the wings 9 of the guard 8, and in this connection it is to be observed that since the wings are provided with the trough-shaped parts 11, the flame can escape readily, from the combustion orifice 7. 65 The guard 8 directs the flame when the structure is used in the open air and under conditions which will suggest themselves readily to the operator.

Having thus described the invention, what 70 is claimed is:—

1. A burner comprising a hollow base and an arch assembled with the base, the crown of the arch having a combustion orifice; and a U-shaped guard straddling the crown of 80 the arch at the combustion orifice, the guard including side wings between which the crown of the arch is insertable, the crown of the arch being gripped between the wings.

2. A burner comprising a hollow base and an arch assembled with the base, the crown of the arch having a combustion orifice; a U-shaped guard straddling the crown of the arch at the combustion orifice, the guard including side wings having outwardly extended trough-shaped parts located adjacent to the combustion orifice and communicating with the space between the intermediate portion of the guard and the crown of the arch.

In testimony that I claim the foregoing as my own, I have hereto affixed my signature in the presence of two witnesses.

LESTER C. FRASER.
